DES. 2108

Adolph Secourte of New York City
Letters Patent No 2108 Dated July 4 1865
Design for Medallion of Abraham Lincoln

The Schedule referred to in this Letters Patent and making part hereof

To all whom it may concern

Be it known that Adolph Secourte, of the City and State of New York, have invented or produced a new and original Design for Medallion of Abraham Lincoln, and do hereby declare the following to be a correct description thereof Reference being had to the annexed photograph of the same.

The design of the said medallion is a profile in bass relief of the late Abraham Lincoln, President of the United States. - Said design is represented by the said photograph and the surroundings of the said profile are formed by a nearly flat surface terminating with a circular and dishing edge.

This medallion is intended to be formed of metal deposited by electricity in a matrix accurately prepared, so as to obtain the sharp and well defined design represented.

What I claim and desire to secure by Letters Patent is the design of the medallion bust in relief as represented.

In witness whereof I have hereunto set my signature this 29th day of May 1865
